INVENTOR.

BY *Walter S. Wallheim*
ATTORNEY.

UNITED STATES PATENT OFFICE.

HARRY E. GILBERT, OF BRIDGEPORT, CONNECTICUT, ASSIGNOR TO HARRY E. GILBERT & SON, OF BRIDGEPORT, CONNECTICUT, A CORPORATION OF CONNECTICUT.

GALVANIZING FURNACE.

Application filed March 31, 1927. Serial No. 179,915.

This invention relates to furnaces, especially the kind used for applying heat to kettles and pots employed for galvanizing and other purposes.

5 Heretofore, in order to protect kettles and pots used for this work, protective walls of high refractory material have been employed and numerous other means have been devised to lengthen the lives of the kettles.

10 None of these, however, have proved to be satisfactory, and fuel costs have increased, rather than decreased. Owing to the inability of regulating properly the heat surrounding the kettles, the heat treating processes in industries such as the galvanizing one, could not be controlled satisfactorily, and the industries involved have been greatly retarded in their development.

It is the object of this invention to sur-
20 mount the aforesaid difficulties and to pro-
vide a furnace which furnishes a steady,
high, and easily controllable, heat to the ket-
tle, in a manner which results in lengthen-
ing the life of a kettle about three times, and
25 one which can be operated at approximately
one-half the fuel cost.

Broadly, the invention is a carrying for-
ward of the principles laid down in Patent
30 #1,489,757, granted to me on April 8, 1924
and applying them to the galvanizing in-
dustry.

A preferred embodiment of the invention
is illustrated by means of the accompany-
ing drawings in which

35 Fig. 1 is a plan view of the furnace;

Fig. 2 is a horizontal longitudinal sec-
tional view along the plane of line 2—2 in
Fig. 4;

40 Fig. 3 is a vertical longitudinal sectional
view along the plane of line 3—3 in Fig. 2;
and

Fig. 4 is a vertical cross sectional view
along the plane of line 4—4 in Fig. 2.

Like numbers of reference denote similar
45 parts throughout the several views and the
following specification.

10 is a substantially rectangular trough-
like kettle. At both sides of the kettle are
heating chambers 11. Each heating cham-
ber extends about one-half way the length
of the kettle 10 and the greater part of its
height. 12 is a combustion chamber for-
ward of the heating chamber of less height
than the heating chamber. 13 is a wall of
55 siliceous material of that side of the heat-

ing chamber 11 which is nearest the kettle 10 and runs parallel thereto but in spaced relation therewith, forming a narrow passage 14 between the kettle and the wall. 15 are perforations through the wall 13 connecting 60 the heating chamber 11 with passage 14. An opposite side wall 16 of the chamber 11 is made of refractory material, and so is a top 17 and bottom 18. A rear wall 19 of the heating chamber 11 is located about mid- 65 way of the kettle and separates a similar chamber in axial alignment with the chamber 11. The rear wall 19 is made of refractory bricks in stepped pier-like form. 20 is an opening at the top of the wall 19 70 communicating with the corresponding heating chamber at the other end of the kettle. In the outer end of the combustion chamber 12 is a throat 21 of siliceous mate-
rial formed with a flaring mouth 22. 23 is 75 a narrow chamber within the rear wall 19 which connects the passage 14 between kettle 10 and side wall 13 with a duct 24 at its bottom which is joined to a passage 25 at the bottom of the kettle, running forward 80 from its point of connection to the duct 24. This passage is open to the bottom of the kettle and is surrounded at the sides and its bottom with refractory material. Forward of the combustion chamber is arranged a 85 trench 26 at right angles thereto, at both ends of the kettle 10. The passage 25 beyond the kettle 10 is surrounded by walls, traverses the trench 26 at its bottom, and is connected to a flue 27, suitably insulated and 90 imbedded in the ground forward of the trench. The entire furnace is about half-way above the floor line. The refractory walls of the chamber 11 are covered with silocel, preferably, for insulating purposes, 95 and the outwardly projecting parts above the floor line are covered, preferably, with iron plates. In the trench 26 is arranged an oil or gas burner 29 in line with the mouth 22, and this is fed from a suitable supply 100 pipe 30 controlled by a valve 31, and also enter-
ing the burner is an air supply pipe 32, to provide the proper mixture. The trench is provided with a suitable cover 33. The cover 33 has been omitted in Fig. 1 of the 105 drawing, and the burner parts from Fig. 2, in order to disclose the construction of the furnace more clearly. 34 is a starting vent in the heating chamber 11.

It will be understood that the heating 110

chamber and fires are arranged at both sides of the kettle, two at each end, the trench at each end extending across both fires.

In operation, the burner being lighted, 5 flames are directed through the mouth 22 into the combustion chamber 12, from which the heat passes to the heating chamber 13, through the openings 15 into passage 14 alongside the kettle, and thence through 10 chamber 23 and duct 24 into passage 25 alongside the bottom of the kettle, and then out into the flue 27. In passing through openings 15 in the wall 13 of siliceous material, the same is heated to incandescence 15 which heats the kettle by radiation, the heat passing through passages 14 and 25 simultaneously heats the kettle by conduction, and the contents of the kettle are heated by convection. Thus I employ the three kinds 20 of transmitting heat, viz, by radiation, by conduction, and by convection, until most of the sensible heat is extracted to a degree that has never before been equalled for these 25 purposes, which is proven by the extraordinary low flue temperatures prevailing in furnaces made in accordance with these principles.

It is obvious that in small kettles and for 30 particular purposes, it is not necessary to surround the kettle with four fires, but two may be sufficient, and when desired, only one fire may be used, the principle of operation and the results obtained, being the same as those described above.

I want it especially understood that, while 35 I have shown the kettle heated by an oil or gas burner, any heating agent may be used, employing either gaseous, liquid, or solid fuel, or electric current, as its source of heat, 40 the burner shown being intended to indicate only one preferred method of applying heat, as well as its preferred location with respect to the combustion chamber.

Various other modifications in form, pro-

portion and combination of parts may be 45 resorted to without departing from the principles of my invention as defined in the appended claims.

What I claim as new, is:

1. A furnace containing a kettle, a fire 50 alongside of the kettle comprising a heating chamber, a combustion chamber forward of the heating chamber, and a heating agent, a perforated wall of siliceous material between the heating chamber and the kettle, 55 a flue forward of the fire, and passages adjacent the kettle for the travel of heat gases from the fire of the flue.

2. A furnace containing a kettle, a fire alongside of the kettle comprising a heating 60 chamber, a combustion chamber forward of the heating chamber, opening into the heating chamber, and a heating agent arranged outside the combustion chamber, a perforated wall of siliceous material between the 65 heating chamber and the kettle, and passages between the said wall and kettle and below the kettle adjacent its bottom, for the travel of heat gases from the fire, the said passages being connected to a flue forward 70 of the fire.

3. A furnace containing a kettle, a fire alongside of the kettle comprising a heating chamber, a combustion chamber, and a heating agent, a perforated wall of siliceous material 75 between the heating chamber and the kettle in spaced relation to the side of the kettle, defining a narrow passage in communication with the said heating chamber, a flue forward of the fire, and a duct adjacent 80 the bottom of the kettle having its one end connected to the rear of the said narrow passage and its other end to the said flue for the travel of heat gases from the fire to the flue.

In testimony whereof I have hereunto set my hand.

HARRY E. GILBERT.
